UNITED STATES PATENT OFFICE

2,267,088

COMMINUTOR

Augustus C. Durdin, III, Chicago, Ill., assignor to
Chicago Pump Company, Chicago, Ill., a corporation of Illinois

Application July 26, 1937, Serial No. 155,710

13 Claims. (Cl. 210—152)

This invention relates to comminutors and particularly to comminutors of the rotary screen type, which are employed for comminuting solids carried by sewage. Certain disadvantages have heretofore been experienced with comminutors of this type. The rotating screen is provided with teeth which carry solid materials against complementary cutting teeth on a stationary cutting bar. Most of the solid materials carried by sewage tend to float on the surface of the liquid and excessive wear is experienced by the teeth and cutting bar adjacent the liquid level. A further disadvantage which has been experienced in comminutors of this type is the tendency for solid material, and particularly pieces of wood of substantial size, to become jammed between the screen and the basin in which it operates. A further disadvantage in prior comminutors is that in some cases elongated floating pieces of debris float through the slots without being engaged by the teeth.

The principal object of the present invention is to provide an improved comminutor in which these disadvantages are eliminated.

Other objects, advantages and capabilities of the invention will appear from the following description of a preferred embodiment thereof, taken in conjunction with the accompanying drawings, in which:

Figure 1 is an elevational view, partly in section, of a comminutor embodying my invention, and associated channels which supply sewage to the comminutor and receive sewage therefrom after passing through the comminutor;

Fig. 2 is a plan view of the comminutor chamber, with the comminutor removed;

Fig. 3 is a sectional detail, taken on the line 3—3 of Fig. 2;

Fig. 4 is a sectional detail, taken on the line 4—4 of Fig. 2;

Fig. 5 is a sectional detail, taken on the line 5—5 of Fig. 2;

Fig. 6 is a sectional detail, taken on the line 6—6 of Fig. 2, and

Fig. 7 is a sectional diagrammatic view showing the manner in which flotsam is caused to be submerged in the normal operation of my comminutor.

Referring to the drawings, the reference number 10 designates a channel for incoming sewage which communicates into the open end 11 of a comminutor chamber 12. This comminutor chamber is preferably substantially cylindrical in plan and its bottom is provided with a downwardly directed channel 13 which is

located in eccentric relation within the chamber 12, as shown in Fig. 2. The passage 13 bends upwardly again, as shown in Fig. 1, and communicates with a channel 14 which conveys the screened sewage away.

At the upper edge of the passage 13, the bottom of the chamber 12 is provided with an annular reinforcing member 15 which is rigidly secured to the concrete from which the chamber 10, chamber 12, passage 13 and channel 14 may be made. The incoming channel 10 may be provided in its bottom with a sump 16 in which is located a bucket 17 for the reception of heavy debris, such as stones, pieces of iron, and the like.

The comminutor or screen is mounted above the annular member 15. This comminutor may suitably comprise a cylindrical screen 18 which terminates near the reinforcing member 15, as best shown in Fig. 7. An annular member 19 of angular cross-section is secured to the reinforcing member 15 so that it lies around the lower end of the cylindrical screen 18. The annular member 19 is provided with a flexible member, for example an annular strip of rubber 20, which bears against the outer wall of the cylinder at its lower end. The screen 18 may be made integral and is provided with a plurality of vertical series of slots 21 through which the liquid may pass inwardly so as to escape down the conduit 13.

Between the adjacent series of slots 21, the screen 18 comprises continuous vertical strips 22 upon which may be mounted cutting teeth 23. The screen 18 is adapted to be driven by a motor 24 and is suspended from a rigid unit which may be carried by beams 25 which extend across the chamber 12. The upper part of the screen 22 is enclosed within a housing 26 which is rigidly secured to a column 27 which extends downwardly along one side of the screen at the position 28 in Fig. 2. Upon the column 27 are mounted cutter bars 29 which are adapted to cooperate with the teeth 23. It may here be noted that a plurality of the teeth 23 are mounted on each vertical strip 22 and that those on adjacent strips 22 are staggered in vertical direction. Consequently, only a few teeth cut each time that one of the strips 22 passes the cutter bars 29, but each tooth of the cutter bars 29 cooperates with the teeth 23 to the same extent during the operation of the machine.

It will be noted, with special reference to Fig. 2, that incoming sewage is directed through the mouth 11 into a chamber which is hook shape in plan and which is reduced in width in the direction of the flow. I arrange the motor 24 to drive the screen 18 in the opposite direction; that is,

in the direction opposite to the direction in which the width of the liquid passage decreases. It will readily be seen with reference to Fig. 2 that if a piece of lumber floats down in the sewage and tends to move into the decreasing passage in the direction of the flow, then it will come into contact with certain of the teeth 23 and will be moved outwardly and drawn by these teeth into a position adjacent the cutter bars 29. Owing to the engagement between the teeth 23 and the teeth of the cutting bars 29, small pieces are cut out of the piece of lumber and this procedure continues until the piece of lumber is disintegrated to the extent that all the pieces may pass through the screen 22.

The manner in which the passage around the comminutor decreases in the direction of flow has been previously described. This decrease compensates for the water which flows through the screen and tends to maintain the level of the liquid constant so that a greater capacity of liquid flow can be obtained. This action is also accentuated by a progressive building up of the channel at the bottom. This is shown in Fig. 3. The bottom of the chamber 12 has a relatively low slope at the position near the beginning of the reducing passage. As shown in Figs. 4, 5 and 6, the slope at the bottom becomes steeper and steeper in the direction of the flow until, as shown in Fig. 6, the slope at the bottom beyond the reinforcing member 15 is approaching the vertical. Owing to the filling up of the decreasing passageway and the high level of liquid maintained therein, the liquid flowing inwardly through the screen sets up a swirling or rotation of the liquid in the reducing passage. This swirling is illustrated in Fig. 7 and it will be noted that it causes the flotsam to become submerged. In this submerged condition certain of the floatable pieces are engaged by the teeth 23 and are conveyed around the passage against the direction of flow into engagement with the cutter bars 29. The cutting action of the comminutor is, therefore, distributed over the submerged portion of the screen 18 and the cutter bars 29 and is not located to an excessive degree adjacent the liquid level.

This rotation or swirling produced in the comminutor chamber also brings elongated solid material to the drum at right angles to the slots, thereby reducing the tendency of such material to align itself parallel to the slots and pass through the slots uncut.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. A comminutor comprising a chamber, a conduit for supplying liquid thereto, a cylindrical screen rotatably mounted within and in eccentric relation to said chamber, an eduction outlet for liquid passing through the screen, said chamber having a wall shaped to define between it and said screen a curved path open at one end and closed at the other into which incoming liquid flows from the open end to the closed end of said path in contact with the screen, cutting means on said screen, stationary cutting means cooperating therewith located near the open end of the said path, and means for driving said screen and its cutting means in a direction oppo-

site to the direction of said flow and toward the open end of said path.

2. A comminutor comprising a chamber, a conduit for supplying liquid thereto, a cylindrical screen rotatably mounted within and in eccentric relation to said chamber, an eduction outlet for liquid passing inwardly through the screen, cutting means on said screen and stationary cutting means cooperating therewith, said chamber and screen defining between them a curved path into which incoming liquid is adapted to flow, said path decreasing in width in the direction of flow, and means for driving said screen in a direction opposite to the direction of flow.

15 3. A comminutor comprising a chamber, a conduit for supplying liquid thereto, a cylindrical screen rotatably mounted within and in eccentric relation to said chamber, an eduction outlet from said chamber below said screen for the escape of liquid passing inwardly through the screen, cutting means on said screen, stationary cutting means cooperating therewith, said chamber and screen defining between them a curved path into which incoming liquid is adapted to flow, the bottom of said chamber being sloped downwardly towards the screen and outlet, said slope becoming greater in the direction of flow, and means for driving said screen.

20 4. A comminutor comprising a chamber, a conduit for supplying liquid thereto, a cylindrical screen rotatably mounted within and in eccentric relation to said chamber, an eduction outlet from said chamber below said screen for the escape of liquid passing inwardly through the screen, cutting means on said screen, stationary cutting means cooperating therewith, said chamber and screen defining between them a curved path into which incoming liquid is adapted to flow, the bottom of said chamber being sloped downwardly towards the screen and outlet, said slope becoming greater in the direction of flow, and means for driving said screen in a direction opposite to the direction of flow.

25 5. A comminutor comprising a chamber, a conduit for supplying liquid thereto, a cylindrical screen rotatably mounted within and in eccentric relation to said chamber, an eduction outlet below said screen for liquid passing inwardly through the screen, cutting means on said screen and stationary cutting means cooperating therewith, said chamber and screen defining between them a curved path into which incoming liquid is adapted to flow, said path decreasing in width in the direction of flow, the bottom of said chamber sloping downwardly towards the screen and outlet, the slope becoming greater as said path narrows in the direction of flow, and means for driving said screen.

30 6. A comminutor comprising a chamber, a conduit for supplying liquid thereto, a cylindrical screen rotatably mounted within and in eccentric relation to said chamber, an eduction outlet below said screen for liquid passing inwardly through the screen, cutting means on said screen and stationary cutting means cooperating therewith, said chamber and screen defining between them a curved path into which incoming liquid is adapted to flow, said path decreasing in width in the direction of flow, the bottom of said chamber sloping downwardly towards the screen and outlet, the slope becoming greater as said path narrows in the direction of flow, and means for driving said screen in a direction opposite to the direction of flow.

35 7. A comminutor comprising a substantially round chamber, a conduit for supplying liquid

thereinto, a cylindrical screen rotatably mounted within and in eccentric relation to said chamber, an eduction outlet below said screen for liquid passing inwardly through the screen, cutting means on said screen, stationary cutting means cooperating therewith located adjacent said conduit and near the position of greatest cross section between the screen and the chamber wall, means adjacent said stationary cutting means preventing flow through that position, said chamber and screen defining between them a curved path into which the incoming liquid is adapted to flow, said path decreasing in width in the direction of flow, the bottom of said chamber sloping downwardly towards the screen and outlet, the slope becoming greater as the path narrows in the direction of flow, and means for driving said screen.

8. A comminutor comprising a substantially round chamber, a conduit for supplying liquid thereinto, a cylindrical screen rotatably mounted within and in eccentric relation to said chamber, an eduction outlet below said screen for liquid passing inwardly through the screen, cutting means on said screen, stationary cutting means cooperating therewith located adjacent said conduit and near the position of greatest cross section between the screen and the chamber wall, means adjacent said stationary cutting means preventing flow through that position, said chamber and screen defining between them a curved path into which the incoming liquid is adapted to flow, said path decreasing in width in the direction of flow, the bottom of said chamber sloping downwardly towards the screen and outlet, the slope becoming greater as the path narrows in the direction of flow, and means for driving said screen in a direction opposite to the direction of flow.

9. The method of comminuting solids carried by liquids which consists in causing said liquid to flow in a converging arcuate path around a screen drum, causing said liquid to swirl upwardly at distances from the surface of said drum and downwardly over the surface of said drum while a portion of the liquid passes into the drum, whereby the normally floating solids are submerged and the normally sinking solids are moved to various heights in said path by the swirling of the liquid in said path said solids are temporarily held against the drum at various heights by the liquid flowing thereinto, rotating the drum, and comminuting the submerged solids carried by the drum at said heights.

10. The method of comminuting solids carried by liquids which consists in causing said liquid to flow in a converging arcuate path around a

screen drum, causing said liquid to swirl axially downwardly over said drum while a portion of the liquid passes into the drum, whereby the solids are submerged by the swirling of the liquid in said path and are held against the drum by the liquid flowing thereinto, rotating the drum in a direction opposite the direction of the flow in said path, and comminuting the submerged solids carried by the drum.

11. The method of comminuting solids carried by liquid which consists in causing said liquid and the solids carried thereby to flow into and out of a circulating path, causing the detained portions of the liquid and solids carried thereby to circulate upwardly and downwardly along different paths, temporarily stopping said solids at various depths along a submerged portion of said path, cutting from said solids small portions thereof at successive stoppings of said solids until such solids are completely comminuted, and removing the cut off and comminuted parts of said solids with the flow of liquid from said up and down circulating path.

12. The method of comminuting solids carried in a flowing liquid stream which consists in causing normally floating and normally sinking solids of said stream to be circulated upwardly and downwardly along different paths, cutting off portions of said solids in their downward flow and at various positions below the surface of the liquid and repeating such cutting operation upon successive arrivals of the solids at their downwardly flowing positions, until the solids have been reduced in size to substantially the size of the portions theretofore cut from the solids and removing the cut off portions of the solids and finally the remaining pieces of the solids from the up and down circulating path.

13. The method of comminuting solids carried by a flowing liquid stream which consists in causing normally floating and normally sinking solids of said stream to be circulated upwardly and downwardly along different paths and horizontally in one direction along a curved path, temporarily stopping said solids at various depths below the surface of the liquid and at various points along said curved path, moving said solids in a direction opposite to said one direction, cutting off portions of said solids below the surface of the liquid, returning the solids to said stream and causing them to be again circulated, stopped and cut until they are reduced to substantially the size of the portions theretofore cut off from them, and removing the cut off portions of the solids and finally the remaining pieces of the solids from said circulating path.

AUGUSTUS C. DURDIN, III.
